UNITED STATES PATENT OFFICE

143,601

DESIGN FOR AN ARC WELDING AND HEAT-TREATING CONTROLLER

Clark C. Kenlan, East Orange, N. J., assignor to
Electric Arc, Inc., Newark, N. J.

Application June 6, 1945, Serial No. 119,930

Term of patent 7 years

(Cl. D26—5)

To all whom it may concern:

Be it known that I, Clark C. Kenlan, a citizen of the United States, residing at East Orange, in the county of Essex, State of New Jersey, have invented a new, original, and ornamental Design for an Arc Welding and Heat Treating Controller, of which the following is a specification, reference being had to the accompanying drawings forming a part thereof.

In the drawings:

Figure 1 is a front perspective view of an arc

welding and heat treating controller showing my new device.

Figure 2 is a view of the side opposite the front portion of Figure 1, both ends of the structure being alike.

I claim:

The ornamental design for an arc welding and heat treating controller, substantially as shown and described.

CLARK C. KENLAN.
